US00D788292S

(12) **United States Design Patent** (10) Patent No.: **US D788,292 S**
Andersen et al. (45) Date of Patent: **** May 30, 2017**

(54) **SUCTION DEVICE FOR NEGATIVE PRESSURE THERAPY**

(71) Applicant: **Mölnlycke Health Care AB**, Göteborg (SE)

(72) Inventors: **Bjarne Andersen**, Frederikssund (DK); **Karsten Videbaek**, Jyllinge (DK)

(73) Assignee: **Mölnlycke Health Care AB**, Gothenburg (SE)

(**) Term: **15 Years**

(21) Appl. No.: **29/537,404**

(22) Filed: **Aug. 25, 2015**

Related U.S. Application Data

(62) Division of application No. 29/458,769, filed on Jun. 21, 2013, now Pat. No. Des. 738,487.

(57) **CLAIM**

The ornamental design for a suction device for negative pressure therapy, as shown and described.

DESCRIPTION

FIG. 1 is a perspective view of a suction device for negative pressure therapy showing our new design;

FIG. 2 is a top thereof;

FIG. 3 is a bottom view thereof;

FIG. 4 is a front view thereof;

FIG. 5 is a rear view thereof;

FIG. 6 is a right side view thereof; and,

FIG. 7 is a left side view thereof.

The broken lines depict portions of the suction device for negative pressure therapy that form no part of the claimed design.

1 Claim, 5 Drawing Sheets
